UNITED STATES PATENT OFFICE.

WILLIAM F. BUBB, OF MOUNTAIN VIEW, CALIFORNIA.

TRIPLE OFFSET FOR PLOWS.

1,102,643.

Specification of Letters Patent.

Patented July 7, 1914.

Application filed April 18, 1914. Serial No. 832,849.

To all whom it may concern:

Be it known that I, WILLIAM F. BUBB, a citizen of the United States, residing at Mountain View, in the county of Santa Clara and State of California, have invented certain new and useful Improvements in Triple Offsets for Plows, of which the following is a specification.

My invention relates to triple offsets for plows and more particularly to that general class of plows known as orchard plows.

The object of the invention is to provide a triple offset for plows of simple and durable construction, capable of being used in orchards for plowing close to the trees, or in any other place where close plowing may be required.

A further object is to provide a triple offset for plows that may be attached to the plow beam of a plow and quickly removed when not required, and an offset that may be quickly adjusted as the operator may require.

A still further object of my invention is generally to improve this class of devices so as to increase their utility, durability and efficiency.

Further objects and advantages will appear in the following description, it being understood that various changes in form, proportions and minor details of construction may be resorted to within the scope of the appended claim.

For a full understanding of the invention and the merits thereof, reference is to be had to the following description and accompanying drawings, in which:

Figure 1 is a plan view of plow beam and triple offset and chain attached thereto. Fig. 2 is a perspective view of offset at plow end of beam. Fig. 3 is a detail view of the eye-bolt.

Corresponding and like parts are referred to in the following description and indicated in all the views of the drawings by the same characters.

The improved triple offsets for plows forming the subject matter of the present invention, comprises an angle iron offset 1 of the required length, width and thickness having upturned flanges as 2. These flanges are for the purpose of strengthening the plow beam and are a part of angle iron offset 1. Said angle iron offset 1 has a brace 55 fastened thereto as shown at 3, said angle

iron offset 1 being fastened to the under side of plow beam 4 near the plow thereof by bolts shown at 5. Near the outer end of angle iron offset 1 is shown a hole bored through said angle iron offset 1 at 6 into which a draft chain 7 or wire rope is fastened. Said draft chain or wire rope 7 extends forward and under plow beam 4 and through eye bolt 8 which is fastened to angle iron offset 9 near the outer end of said plow beam 4 by nut 10, and connects with offset plate 11 by hook device 12 passing through offset hole 13 bored in offset plate 11. Said angle iron offset 9 is made of iron or steel of the required length, width and thickness, and is fastened near the outer end of plow beam 4 by bolts shown at 14 the offset portion thereof having a plurality of holes 15 bored therethrough for the purpose of adjusting the offset required at this point by inserting therein eye-bolt 8 through which chain or wire rope 7 passes. Offset plate 11 may be made of iron or any other suitable material of the required length, width and thickness, having holes bored through the same near the ends thereof as shown at 16 which are for the purpose of connecting offset draft chains 17 to draw bar 18, the inner chain being shorter than the outer chain for the purpose of offsetting swingle-tree 18. Said chains are connected with swingle-tree 18 near the ends thereof in any suitable manner. This swingle-tree 18 may be made of wood or any other suitable material of the required width and thickness and of any length that may be required as it is often found that three or more horses may be worked abreast to advantage. Connecting to swingle-tree 18 by clevises 19 are shown whiffletrrees 20, to which horses are attached.

My improved device is simple in construction, can be secured to any ordinary plow beam, is of few parts, and can be manufactured at a small initial cost.

It is evident that slight changes in the construction of the different parts might be resorted to without departing from the spirit of my invention, and hence I would have it understood that I do not limit myself to the exact construction shown and described, but consider myself at liberty to make such slight changes and alterations as fairly fall within the spirit and scope of my invention.

Having fully described my invention,

what I claim as new and desire to secure by Letters Patent, is—

In a triple offset for plows, the combination of an angle iron offset having upturned flanges thereon and a brace attached thereto, means by which said angle iron offset is attached to the under side of a plow beam, a draft chain or wire rope attached to said angle iron offset extending forward and under said plow beam, an angle iron offset fastened on the top and near the outer end of said plow beam, a plurality of holes bored through said offset portion of said angle iron adapted to engage an eye-bolt through

which a chain or wire rope passes connecting with an offset plate to which is connected at its ends by offset draft chains of different lengths, said chains connecting with a swingle-tree, means by which said swingle-tree is connected to whiffletrees, as and for the purpose described.

In testimony whereof I affix my signature in presence of two subscribing witnesses, this 9th day of April, 1914.

WILLIAM F. BUBB.

Witnesses:

JOHN A. NAISMITH,
L. I. JONES.
